(57) **CLAIM**

The ornamental design for a bath screen with the supporting bar, as shown and described.

DESCRIPTION

FIG. 1 is a front elevational view of a bath screen with the supporting bar showing my new design;

FIG. 2 is a rear elevational view thereof;

FIG. 3 is a left side view thereof;

FIG. 4 is a right side view thereof;

FIG. 5 is a perspective view thereof;

FIG. 6 is a second perspective view thereof;

FIG. 7 is a third perspective view thereof;

FIG. 8 is an enlarged view of portion 8 shown in FIG. 6; and,

FIG. 9 is an enlarged view of portion 9 shown in FIG. 6.

The dash-dot lines in the drawings do not form part of the claimed design.
